CLOSURE DEVICE

Bernard Nicolas Lafarge, Sevres, France

Application July 20, 1948, Serial No. 39,652
In France November 14, 1947

5 Claims. (Cl. 220—43)

1

The object of the present invention is to provide an improved lid for closing tins, cans or other containers, which may be provided with spouts and, which, from their opening downward, are first provided with a cylindrical surface on to which the lid is adapted to fit, without play, by means of a corresponding cylindrical portion, and then preferably with a keeper or bead limiting the penetration of the lid. In such containers or cans, for example in the usual shoe polish tins, it is not easy to remove the lid and even to put it back in place.

An object of the invention is to provide a lid which is so designed as to facilitate the above operations, in particular the removal of the lid.

According to the invention, the cylindrical portion of said lid, portion which is intended to fit on to the cylindrical surface of the can or other container, is extended at least over a part of its periphery by at least a flared extension which tapers away from the longitudinal axis of the lid.

Said flared extension facilitates: on the one hand, the removal of the lid, either by means of a radial pressure which is exerted on same and which, by pressing said extension toward the can (or other container), causes a slight deformation of said lid which facilitates the disengagement thereof, and, on the other hand, the placing in position of the lid by guiding same.

It is possible to provide either a continuous flared flange extending over the entire periphery of the lid, or one or more projections (or lugs), for example two projections diametrically opposite one another.

Other features will become apparent from the following description.

In the accompanying drawing, which is given solely by way of example:

Fig. 1 is a diametrical section of a lid according to the invention, positioned on a tin of the usual shoe polish type;

Fig. 2 is a top plan view of the lid;

Figs. 3 and 4 are fractional diametrical sections showing modifications of shapes of the extension of the lid;

Figs. 5 and 6 are top plan views of lids, respectively with two diametrically opposite projections and with a single projection;

Fig. 7 is a diametrical section, along the line 7—7 of Fig. 8, of another modification;

Fig. 8 is a corresponding plan view;

Fig. 9 is a longitudinal section, along the line 9—9 of Fig. 10, of another modification;

Fig. 10 is a corresponding elevational view.

According to the embodiment illustrated in

2

Figs. 1 and 2, the closure device according to the invention is assumed to be applied to a tin box 1, of the type commonly used for shoe polish and like products, said box being provided, as from its upper opening 2, with a cylindrical portion 3 which is provided with a keeper or bead 4.

The lid according to the invention is provided, as from an upper end 5 which is flat, or recessed at 6, with the usual cylindrical portion 7 intended to fit without play over the portion 3 of the tin 1. Said cylindrical portion 7 is extended by a flared portion or prolongation 8 of frusto-conical shape which is preferably bound by a small cylindrical edge 9. The angle at the top of this frusto-conical portion 8 is such that said portion fits over the bead 4 of the tin with a slight clearance when the lid is fitted right home on said tin, as shown in Fig. 1.

When the opening of the tin as illustrated in Figures 1 and 2 is desired, in order to disengage the lid, it is possible to press in two diametrically opposite directions, for example in the directions of f^1 and f^2 (Figs. 1 and 2) against the frusto-conical extension 8; said extension is resiliently deformed and soon bears at a and b (Fig. 1) against the rigid bead 4 of the tin and to some extent forms a lever arm, producing a slight pull in the direction of f^3 and f^4 on the cylindrical portion 7 of the lid; consequently a slight ovalisation of the lid is produced, which facilitates its disengagement.

On the other hand, extension 8, owing to its flared shape, considerably facilitates the replacement of the lid in position, since it is only necessary to fit the extension over the tin without taking any special care; owing to its conical shape, said extension guides the lid on which just a pressure is necessary in order to cause it to engage, no matter how accurately it is adapted to fit on the tin or other container.

In Fig. 3, a modification has been shown where-in the extension of frusto-conical shape is terminated by a rolled edge 10.

Naturally, the shape of the extension may be other than frusto-conical; Fig. 4 shows a section 11 which is more or less curved in bell-shape.

In the modification shown in Fig. 5, the flared prolongation of the lid (shown at 8 in Figs. 1 and 2) is not extended over the entire periphery of the lid, but only over two diametrically opposite portions 12 and 13.

Fig. 6 shows another modification, wherein only one projection 14 is provided which extends only over a small portion (about one-fourth) of the periphery of the lid.

Of course, any other similar arrangement may

be adopted, it being possible to reduce the extension or the separate extensions to narrow lugs which are divergent relatively to the longitudinal axis of the lid.

The lid according to the invention may be readily adapted to receive a guarantee strip.

Thus, in the example of Figs. 7 and 8, the two extensions 12 and 13, which are similar to those of Fig. 5, are themselves extended by two lugs 14, 15 which are more or less horizontal and bent over at 16 and 17 so as to grip one of the ends of two guarantee strips 18 and 19 which may be cemented or otherwise fixed by their other ends to the body of the box 1. Before the lid is placed in position, the two strips 18 and 19 may advantageously form a single strip which is transversely stretched between the two lugs 14 and 15 and which is adapted to be cut at its central portion when the lid is to be fitted.

Figs. 9 and 10 show another embodiment wherein the extension 20 is curved towards the axis of the lid. Its lower opening 21 is nevertheless of larger size than the bead 4 of the tin 1, and said extension is extended by one or more resilient tongues 22 which are bent towards the longitudinal axis of the lid and are intended to press against the body of the tin so that they can be covered by a guarantee strip 23. Owing to its resilience, the tongue 22, or each of them, does not hinder the placing in position or the removal of the lid, since it is easily deformed temporarily as it passes over the bead 4. Each tongue 22 may advantageously be provided at its lower end with an outwardly directed flange 24 intended to retain the lid by engaging the strip 23.

Naturally, the invention is in no way limited to the embodiments illustrated and described, which have only been chosen by way of example.

Having now described my invention what I claim as new and desire to secure by Letters Patent is:

1. An article of manufacture comprising: a container including a bottom wall, a side wall and a bead formed on said side wall spaced downwardly from the top edge of said side wall forming in the latter a rim portion above said bead; a closure including a top wall, a lateral portion extending downwardly from said top wall and fitting over said rim portion and terminating a short distance above said bead; resilient lever-

forming means extending from at least a part of the lower edge of said lateral portion, said means having a flaring profile sloping simultaneously and continuously away and downward from said lower edge, the lower portion of said means being spaced a substantial distance below and beyond said bead, said means being most closely adjacent to the upper half of said bead along a line parallel to said lower edge and located between said lower edge and said lower portion, said means being sufficiently close to said bead to contact said upper half of said bead along said line and to fulcrum theron under the application of inwardly directed pressure, whereby said closure will be disengaged from said container by the application solely of said pressure.

2. An article of manufacture as claimed in claim 1, in which the profile of said resilient lever-forming means is frusto-conical.

3. An article of manufacture as claimed in claim 1, in which said lever-forming means extend along the entire periphery of said lower edge.

4. An article of manufacture as claimed in claim 1, in which said lower portion of said resilient lever-forming means is further prolonged by a cylindrical flange extending downward substantially parallel to said side wall.

5. An article of manufacture as claimed in claim 1, in which said lower portion of said resilient lever-forming means terminates at its bottom edge by a rolled edge.

BERNARD NICOLAS LAFARGE.
